UNITED STATES PATENT OFFICE

124,731

DESIGN FOR AN ADVERTISING FIGURE OR SIMILAR ARTICLE

Arthur R. Wells, Jr., Quincy, Mass.

Application September 26, 1940, Serial No. 95,415

Term of patent 7 years

To all whom it may concern:

Be it known that I, Arthur R. Wells, Jr., a citizen of the United States of America, residing at Quincy, in the county of Norfolk, in the Commonwealth of Massachusetts, have invented a new, original, and ornamental Design for an Advertising Figure or Similar Article, of which the following is a specification, reference being had to the accompanying drawing, forming a part thereof.

I claim:

The ornamental design for an advertising figure or similar article, substantially as shown and described.

ARTHUR R. WELLS, JR.
